UNITED STATES PATENT OFFICE.

ALVIN G. SHERMAN, OF DETROIT, MICHIGAN.

DESIGN FOR A GAS-BURNER.

42,339.

Specification for Design.

Patented Mar. 19, 1912.

Application filed November 8, 1911. Serial No. 659,256. Term of patent 14 years.

To all whom it may concern:

Be it known that I, **ALVIN G. SHERMAN**, a citizen of the United States, residing at Detroit, in the county of Wayne and State of Michigan, have invented a new, original, and ornamental Design for Gas-Burners, of which the following is a specification, reference being had to the accompanying drawing, forming part thereof.

The figure is a front elevation of a gas burner showing my new design.

I claim:

The ornamental design for a gas burner, as shown.

ALVIN G. SHERMAN.

Witnesses:

**STUART C. BARNES,
AGNES HIPKINS.**
